UNITED STATES PATENT OFFICE

1,926,827

CALCULATING MACHINE

Joseph A. V. Turck, Wilmette, Ill., assignor to
Felt & Tarrant Manufacturing Company,
Chicago, Ill., a corporation of Illinois

Application April 30, 1929. Serial No. 350,261

2 Claims. (Cl. 235—82)

This invention relates in general to improvements in calculating machines, and more particularly to improvements in key-operated calculating machines of the multiple order type.

Objects of the invention are to provide an arrangement whereby the machine is mounted within a desk top with the top casing of the calculating machine substantially flush with the desk top, so that vision of the key tops and the records from which an operator may be calculating items are brought much nearer to a level, which is of special advantage when operators are required to handle records of large capacity and dimensions; to provide for assembly of calculating machines within a desk top so that the desk itself forms a rigid supporting casing for the operating mechanism of such machines, whereby machines of large ordinal capacity, such as machines ranging upwardly in ordinal capacity from sixteen ordinal places, may be rigidly supported against twisting and sagging to which they would be subjected, by reason of the flexibility of casings therefor resulting from the length thereof required for enclosing machines of such large ordinal capacity, were they mounted in the customary manner in the usual casings heretofore employed for rigidly supporting similar machines, but of much smaller ordinal capacity, in which such twisting and sagging does not obtain because of the fact that the relatively small number of ordinal mechanisms therein are not of such length as to require a casing of such length that flexing of the casing would inherently result from the length thereof; to provide for assembly of calculating machines within a desk top so that the desk itself forms a casing for such machines and the top casing of the calculating machine bridges the desk opening in which the machine is mounted and seals said opening; to have all of the mechanism of the calculating machine below the normal surface of the desk top, except the manipulative devices for operating the machine; to provide a neater and more practical mounting of a calculating machine on a desk top than prior mountings in which the actuating mechanism was encased in a casing and the casing placed on top of the desk so as to be mounted above the level thereof; and the invention has for other objects such other advantages and results in construction and operation as may be found to obtain in the structure hereinafter described or claimed.

In the accompanying drawings, forming a part of this specification, and showing for purposes of exemplification, a preferred form and manner in which the invention may be embodied and prac-

ticed, but without limiting the claimed invention specifically to such illustrative instance or instances:

Figure 1 is a perspective view of a desk having a calculating machine assembled in the top thereof, and showing the invention as embodied in an ordinary type of flat top desk; 60

Fig. 2 is a top plan view of a part of the assembly of Fig. 1 and showing the keyboard and other manipulative devices of the calculating machine; 65

Fig. 3 is a view partly in cross-section and partly in side elevation showing the depressed casing of the machine in cross-section, and the right hand side of a part of the mechanism of the calculating machine in elevation; 70

Fig. 4 is a view taken on the line 4—4 of Fig. 5 showing a right side elevation of a part of the zeroizing mechanism of the machine, and a cross-section of the casing through which the manipulative devices of the zeroizing mechanism extend; 75

Fig. 5 is a vertical cross-sectional view taken on the line 5—5 of Fig. 4 and showing the manipulative device of the zeroizing mechanism and its relationship to the top casing or key-plate of the machine. 80

In its present embodiment the invention is applied to the assembly in a desk of a calculating machine of the multiple order key driven type, such as shown in United States Letters Patent No. 1,072,933 to Dorr E. Felt, and others to Dorr E. Felt, and also in United States Letters Patent No. 1,110,734 to Kurt F. Ziehm, and United States Letters Patent Nos. 1,357,747, 1,357,748, 1,367,468 and others to the present inventor Joseph A. V. Turck. For convenience the ensuing description will be directed to this use of the invention. The novel features of the present invention are, however, readily susceptible of other valuable application, for example, with other types of adding or calculating machines, such as key-driven or key-set adding or calculating machines, hence the invention is not confined to the specific use and specific embodiment herein described as an illustrative example. 90

Referring to the drawings:—

10 indicates a desk of an ordinary type of flat top desk having two sets of drawers 11 spaced from each other, as usual, and having a flat top 13 extending over the two sets of drawers 11 and the space between said two sets of drawers. The portion of the top 13 over the space between the two sets of drawers 11 is provided with a rectangular opening 14 extending close to the front edge of the desk and of substantially the same width and length as the width and 105

100

105

110

length of a calculating machine that is to be mounted within said desk top with its operating mechanism beneath and its manipulative devices above the surface of the desk. Depending from 5 and in substantial alignment with the marginal edges 15 is a metallic casing 16 having sides 17 and ends 18 connected with each other by a bottom 19. The casing 16 encloses the calculating machine opening 14, below the top surface of the 10 desk, and is of sufficient depth to receive and support a calculating machine therein with all of its operating mechanism below and all of its manipulating devices for actuating the operating mechanism above the top surface of the 15 desk. The casing 16 is, in the present embodiment of the invention, formed integral with the desk, being secured thereto by marginal flanges 20 that extend outwardly laterally from the sides 17 and ends 18 and that are welded or otherwise rigidly secured to the top metallic plate 21 of the desk. The top metallic plate 21 may be 20 and, as shown, is covered with a covering 22 of soft material.

23 indicates a calculating machine arranged 25 and adapted for mounting within the desk 10 and having a top or key-plate 24 for covering the operating mechanism 25 beneath the said plate 24, and having all of its manipulative devices 26 for actuating the operating mechanism 25 30 extending through and above the top casing or key-plate 24. The top casing plate 24 is extended beyond the side casing members 17 and the front and back casing members 18 so as to bridge the desk opening 14 for the machine and extend 35 beyond the marginal edges 15 of the desk opening when the machine is mounted within said opening. The top casing plate 24 is shaped to conform to and form a continuation of the surface of the desk top in substantially the plane thereof so that when assembled within the desk opening 14 it will be substantially flush with the desk top 13 and will seal said desk opening 14 for the machine.

40 The manipulative devices of the calculating 45 machine comprise depressible keys 30 for actuating the operating mechanism, subtraction levers 35, a zeroizing lever manipulative device 51, and the operating mechanism comprises ordinal actuating mechanism, indicated generally by the 50 reference numeral 32, ordinal accumulator mechanism, indicated generally by the reference numeral 31, and zeroizing mechanism, indicated generally by the reference numeral 37.

55 As the details of construction of this type of machine may be readily understood from said United States patents, a brief description of the general features of this type of machine, and such parts as are directly concerned with the operation of the present improvement, will be sufficient for an understanding of this invention.

60 The various instrumentalities of the calculating machine are supported by a frame constituted of side skeleton plates 27 and intermediate skeleton plates 27' disposed between the various actuating mechanisms of the several orders of the machine and all tied together at suitable points by the rods 28. A number of columns 29 of nine keys, which constitute a part of the manipulative devices of the machine are provided, each key being indicated by the reference numeral 30, there being a column of nine keys for each numeral wheel 31, that is a duplicate of the other columns, together with actuating and attendant parts interposed between each 65 of the columns of keys and its corresponding

numeral wheel 31. The actuating mechanism corresponding with each column of keys 29 and its numeral wheel 31 includes a column actuator 32 pivoted at the rear end of the machine and adapted to be depressed in different amounts, as determined by the particular key 30 manipulated by an operator. Each key 30 is provided with a stem 33 extending down and bearing on the corresponding column actuator 32. The column actuator for each order or column 29 of 80 nine keys is moved upwardly on release of an actuated key 30 by column actuator springs 34, and is adapted to impart calculating movement to the accumulator mechanism 31 at the front of the machine of which the numeral wheels 85 form a part, all as will more fully appear from said prior patents above referred to.

90 Zeroizing of the accumulator mechanism 31 is effected by oscillation of zeroizing shaft 43. Such zeroizing oscillation of shaft 43 is obtained 95 through operation of the following described mechanism shown more particularly in Figs. 3, 4 and 5.

99 A short transverse rod 36 is journaled in a bearing in the right hand side plate 27 of the 100 frame. A zeroizing segment lever 37 is fixed upon said shaft 36 and pivoted to said segment 37 is a link 38 which is in turn pivoted to a depending lever arm 39 that is pivoted at 40 on the fixed frame. The lower end of said lever 105 arm 39 is pivotally connected by means of a short link 41 with an arm 42 rotatably mounted with respect to a transverse shaft 43 that is journaled in the fixed frame. The arm 42 is provided with an engaging face 44 adapted to 110 make contact with a second arm 45 fast on shaft 43. A short swinging movement of the lever 37 to the left will, through link 38, lever arm 39, short link 41, arm 42 and rocker arm 45 impart a short rocking oscillatory movement to the shaft 115 43, in a counter-clockwise direction. Such rocking movement, through known appropriate mechanism connecting the shaft 43 with the accumulator mechanism 31, serving to effect zeroization of the accumulator mechanism 31, as by effecting 120 detrainment of the accumulator mechanism from the actuating mechanism for restoring the numeral wheels to zero.

125 The calculating machine, after being completely assembled in the framework, comprising 125 the skeleton plates 27 and 27', with the operating mechanism below the top casing plate 24 and the manipulative devices extending through and above the top casing plate, is lowered into the desk opening and mounted therein so that 130 the top casing plate 24 engages over the top covering 22 of the desk and is substantially flush therewith and bridges and seals the desk opening 14. Bars 46 are arranged in contact with the under side of the casing plate 24 on opposite 135 sides of the machine and extend from the front to the back thereof so as to engage the marginal edges 15 in order to facilitate alignment of the machine in the desk and to maintain the mechanism true therein.

140 Heretofore, owing to the fact that calculating machines have been assembled in casings especially designed to cover their operating mechanisms, the manipulative devices for actuating the zeroizing lever 37 have been arranged to 145 project through the side of the casing. Such form of construction is not especially suitable to the mounting of calculating machines with a desk top so that the top casing plate bridges the desk opening and is substantially flush with and seals

the desk opening. To this end, the lever 37 is rigidly connected with a sector lever 47, which, for assembly purposes, are keyed and held together by a screw 48 and a dowel stud 49. A flanged sector plate 50 is rigidly secured to, or formed as a part of, sector lever 47 and is provided with a slotted flange 50' curved longitudinally of the ordinal columns of the machine on a radius with the pivot point of the zeroizing lever 37. A finger manipulative arm 51 is fastened at its lower end to the sector lever 47 by a screw 52 and extends upwardly through the slot in the flange 50' above the upper surface of the top plate, so as to be above the top level of the desk, and is provided with a curved finger piece 53 at its upper end for manipulation of the levers 47 and 37. With this construction, when the finger is placed on the curved finger piece 53 and drawn toward the front of the machine, zeroizing oscillation or rocking of the shaft 48 occurs, and the same zeroizing action described in my aforesaid Patent 1,357,748 is produced by a mere single finger manipulation without other application of power.

To house the lever 47 and arm 51, the top casing or key-plate 24 is formed to provide two upwardly projecting vertical sides 54 and an arcuate top 55, that connects the sides 54, with its radius center conforming with that of the zeroizing lever 37. The arcuate top 55 is formed on a slightly greater radius than the flange 50' of the sector 47 so as to provide for circular motion of the flange 50' during manipulation of the finger piece 53. The arcuate top 55 of the key-plate 24 is provided with a slot 56 through which the arm 51 protrudes and rides during manipulation of the finger piece 53 to zeroize or clear the numeral wheels, as hereinbefore described. The width of the slot 56 is preferably such as to give a slight clearance on each side of the arm 51, and long enough to be clear of it on each forward arcuate movement of said arm. With this arrangement of the flange 50' in close proximity to the arcuate top 55 and extending on opposite sides of the arm 51, toward the front and back of the machine, the flange 50' covers the slot 56 at any position of the sector arm 51.

It is highly desirable to have the sight apertures 58, for reading the answers or totals on the numeral wheels of the accumulator 81 through the top casing plate 24, arranged in the top casing plate so that the register reading will be in direct line of vision with the normal position of an operator during operation of the machine. Such advantageous feature is attained by curving the top casing plate 24 at 59 around the forward parts of the numeral wheels and by having the sight apertures 58 arranged at an angle with a line running parallel with the keyboard. In order to embody such advantageous feature in the present construction and to have the top casing plate substantially flush with the desk top at the front marginal edge 60 of the desk opening, the top casing plate is depressed lengthwise of the series of sight openings and immediately in front thereof to form a cupped or longitudinally extending concave depression 60. Such cupping provides the curve 60 in the top plate 24 around the registering wheels for true vision through the sight apertures 58, and brings the lines of the top casing 24 back to the level of the top of the desk. The portion of the top casing plate containing the sight apertures 58 and the cupped depression 60 is formed

as a separate piece 61 from the remainder of the top casing plate for convenience of punching the sight openings and forming the cupped depression, and to facilitate assembly of the top casing plate with respect to the subtraction levers 35. 60 However, the entire top plate 24 may be made in a single piece if desired.

Brackets 62 are secured to the front end of the casing plate and to the front ends of the skeleton plates 27 and 27' to support the separate piece 61.

In commercial use of machines of the type above described, machines of different columnar capacity are required. In the drawings, a 10-column type of machine is illustrated, but it is of course understood that the invention is not confined to any specific number of columns. In other words, any number of columns may be provided, and columns up to forty or fifty can easily be provided with the assembly and construction of the present invention. The calculating machine casings of the type heretofore employed for maintaining rigid and for supporting with respect to each other the ordinal operating mechanisms of calculating machines, while very effective for such purpose in machines of relatively small ordinal capacity, for example up to ten or fifteen ordinal mechanisms, are not sufficiently effective for such purpose in calculating machines ranging upwardly in ordinal capacity 100 from, for instance, sixteen ordinal mechanisms. The casing, by reason of the greater length thereof, is not rigid enough to prevent twisting of, and does not provide adequate support to prevent sagging of, the ordinal mechanisms of calculating machines of such relatively large ordinal capacity. With the manner of assembly and the arrangement of desk and calculating machine of the present invention, the rigidity of the desk affords a very effective and practical and rigid support for the more numerous ordinal mechanisms of calculating machines of such relatively large ordinal capacity. Thus, the present invention, while of considerable merit in connection with calculating machines in general is of particular utility and is especially advantageous when employed in connection with calculating machines of such relatively large ordinal capacities. In instances where machines of large ordinal capacity are employed, bars 63 are provided as cross-supports in the casing.

The invention as hereinabove set forth is embodied in a particular form but may be variously embodied within the scope of the claims herein-after made.

I claim:

1. A work-desk or table having a top with a calculating machine opening therein, a calculating machine mounted within said opening with its actuating mechanism and accumulator mechanism therefor inset entirely below the level of the top of the desk and its manipulative devices for actuating the actuating mechanism extending above the top of the desk, and a top casing plate separating the manipulative devices from the inset mechanism and forming a substantially flush plane with the top surface of the desk or table top and with all of the marginal portions of the top casing plate substantially flush and contiguous with and forming a continuation of the top surface of the desk or table top, so that vision and the operable surfaces of the tops of the manipulative devices and records on the adjacent table top are brought to a substantially common level thereby so coordinating visual translation of fig- 150

ure-work from the table-top with facile manipulation of the operating devices as to increase greatly the effective capacity of the calculating machine when so mounted.

5 2. A work-desk or table having a top with a calculating machine opening therein, a calculating machine having a lower casing and a top casing plate enclosing a row of numeral wheels and actuating mechanism and accumulator 10 mechanism therefor and having its manipulative devices extending through the top casing plate in fixed relationship therewith; said machine being inset within the opening of said top with the top casing plate forming a substantially flush 15 plane with the top surface of the desk or table top and with the marginal portions of the top casing plate substantially flush and contiguous

with, and forming a continuation of, the top surface of the desk or table top; and said top casing plate having a longitudinal concave portion provided with sight apertures adjacent the numeral wheels to facilitate reading thereof, said concave portion being inside of and surrounded by the aforesaid flush plane forming marginal portions of the top casing plate, so that vision and the operable surfaces of the tops of the manipulative devices and records on the adjacent table top are brought to a substantially common level, thereby so coordinating visual translation of figure-work from the table-top with facile manipulation of the operating devices as to increase greatly the effective capacity of the calculating machine when so mounted.
